UNITED STATES PATENT OFFICE.

THOMAS J. BURY, OF HOUSTON, TEXAS.

FENDER BRACE.

Application filed May 13, 1922. Serial No. 560,559.

To all whom it may concern:

Be it known that I, THOMAS J. BURY, a citizen of the United States, residing at Houston, in the county of Harris and State 5 of Texas, have invented certain new and useful Improvements in Fender Braces, of which the following is a specification, reference being had to the accompanying drawings.

10 It has been found that the front and back fenders of automobiles especially those of the Ford type become misplaced, rattle, and sag down on the tires, which results in wear on the structure, therefore it is the purpose 15 of the present invention to provide a device of this character which will hold the fenders clamped in position, prevent all rattling, and make the fenders strong and more durable.

Another purpose is to provide a brace 20 which will prevent the fenders from sagging down and causing wear on the tires, as well as preventing distortion of the fenders.

Still another purpose is to provide a fender brace comprising clamps connected to and 25 carried by the fenders, in combination with a transverse rod adjustably connecting the clamps, to insure rigidity, strength and durability. This brace may be adjusted on the fenders from a position adjacent the radi- 30 ator forwardly, and is capable of being applied either to the front or back fenders, or both, preferably the latter. It is to be noted that the brace is not limited to use in connection with Ford automobiles, for it is ob- 35 vious that it may be used on other makes.

It is to be understood that the particulars herein given are in no way limitative and that while still keeping within the scope of the invention, any desired modifications of 40 detail and desired proportions may be made in the apparatus according to circumstances.

The invention comprises further features and combination of parts, as will be herein- 45 after set forth, shown in the drawings and claimed.

In the drawings:—

Figure 1 is a view in perspective of the front portion of an automobile, showing the clamps as applied to the fenders, together 50 with the reinforcing connecting rod, which adjustably connects the clamps; and

Figure 2 is an enlarged detail view of the fender brace detached.

Figure 3 is a vertical longitudinal section 55 through one of the clamps and a portion of the fender.

Referring to the drawings, 1 and 2 designate the fenders, which may be those of the front or back of the vehicle, preferably the front, and 3 and 4 designate the clamps. 60 Each clamp comprises a piece of sheet or bar material, which is bent upon itself as at 5, and the opposed parts are laterally bent in opposite directions as at 6. Prior to applying the clamp the opposed parts 7 between 65 the bends 5 and 6 diverge, but when the clamp is properly applied and adjusted, these opposed parts 7 are drawn toward and adjacent each other, so as to draw the hooked ends 8 of the lateral parts 9 of the clamp 70 tightly and securely in engagement with the opposite edges of the fender. In other words the hooks 8 at the ends of the lateral parts 9 grip the opposite edges of the fender, and hold the same rigid, and materially prevent 75 rattling and sagging of the fender.

The opposed parts 7 between the bends 5 and 6 are provided with registering openings or apertures 10, which receive the threaded ends 11 of a transverse brace rod 80 12. This transverse rod 12 may be disposed adjacent the front of the radiator, or forwardly thereof, it depending entirely upon the conditions and the ideas of the owner of the vehicle. Preferably the rod 12 is disposed adjacent the radiator. When the rod 12 is applied the nuts 13 are threaded on the ends of the rod, so that such nuts may contact with the outer faces of the inner portions 7 of the clamps, thereby constituting 85 abutments. In fact when the opposed parts 7 are drawn toward each other, an upstanding lug is formed on the clamp. After the nuts 13 are applied, and adjusted to the proper locations, additional nuts 14 are threaded upon the extremities of the threaded ends of the rods, and are adjusted toward and in contact with the outer faces of the remote parts 7 of both clamps. When the nuts 14 are tightened in place, they not only insure 90 a rigid brace or connection between the opposite fenders, but also act to draw the opposed parts 7 in contact with each other, and also insure a rigid grip of the hooks 8 with the opposite edges of both fenders. 105

A construction of brace of this character will not only insure rigidity between the fenders, but will also prevent rattling, and hold them in place and prevent them from sagging or dragging upon the tires of a 110 wheel, which will result materially in rendering the fenders more durable. Obviously

the fender brace may be applied to the rear fenders as well as to the front fenders.

The invention having been set forth, what is claimed is:—

- 5 The combination with the opposite fenders of an automobile, of a pair of clamps, each clamp comprising a piece of bar material bent upon itself causing to be formed adjustable separable parts and lateral arms
- 10 having grips at their remote ends for gripping the opposite edges of the fenders, a transverse element having its ends passing through the separable opposed parts of the clamps, said transverse reinforcing element

having means for drawing the separable parts together and adjustably connecting the clamps to the element, each clamp having arms extending laterally in opposite directions and terminating in fender grips, for engagement with the opposite edges of the fender, and holding the fender rigid, when the separable parts of the clamp are drawn toward and relatively adjacent each other, to insure a clamping action.

In testimony whereof I hereunto affix my signature.

THOMAS J. BURY.
